(57) **CLAIM**

The ornamental design for an identification/security card holder, as shown and described.

DESCRIPTION

FIG. 1 is a perspective view of an identification/security card holder showing my new design;

FIG. 2 is a top view thereof;

FIG. 3 is a bottom view thereof;

FIG. 4 is a side view thereof;

FIG. 5 is another side view thereof;

FIG. 6 is a rear view thereof; and,

FIG. 7 is the front view thereof.

The uneven broken line representations in FIGS. 1-5 are illustrative of environment and form no part of the claimed design.

1 Claim, 3 Drawing Sheets

FIG. 1

FIG. 2**FIG. 3**

FIG. 4**FIG. 5****FIG. 6****FIG. 7**
